[57] CLAIM

The ornamental design for a pedestal lavatory, as shown and described.

DESCRIPTION

FIG. 1 is a top front perspective view of a pedestal lavatory showing my new design;

FIG. 2 is a front elevational view thereof;

FIG. 3 is a cross-sectional view taken on line 3—3 of FIG. 2;

FIG. 4 is a cross-sectional view taken on line 4—4 of FIG. 2;

FIG. 5 is a top plan view thereof;

FIG. 6 is a bottom plan view thereof;

FIG. 7 is a right side elevational view thereof, the left side elevational view being the mirror image of the right side shown; and,

FIG. 8 is a cross-sectional view taken on line 8—8 of The fragmentary broken line representations of holes in FIGS. 1 and 5 are for the purpose of illustration only and form no part of the claimed design.

FIG. 1

FIG. 5

FIG. 6

FIG. 7

FIG. 8
